SOFT WRAPPINGS CUTTER

Leonard W. Cheslak, 13552 Arizona,
Westminster, Calif. 92683

Filed June 26, 1968, Ser. No. 12,509

Term of patent 14 years

Int. Cl. D8—02

U.S. Cl. D95—3

FIG. 1 is a perspective view of the soft wrappings cutter;
FIG. 2 is a top plan view of the soft wrappings cutter
of FIG. 1;

FIG. 3 is a bottom plan view of the soft wrappings
cutter of FIG. 1;

FIG. 4 is a left side elevation view of the soft wrap-
pings cutter of FIG. 1;

FIG. 5 is a front elevation of the soft wrappings cutter
of FIG. 1;

FIG. 6 is a rear elevation of the soft wrappings cutter
of FIG. 1;

FIG. 7 is a cross-section of the soft wrappings cutter
taken along line 7—7 of FIG. 4.

I claim:

The ornamental design for a soft wrappings cutter, sub-
stantially as shown.
